G. L. BONHAM,
SPRING MOTOR BRAKE,
APPLICATION FILED JAN. 18, 1915.

1,143,030.

Patented June 15, 1915.

UNITED STATES PATENT OFFICE.

GUY L. BONHAM, OF WEST HARTFORD, CONNECTICUT.

SPRING-MOTOR BRAKE.

1,143,030.

Specification of Letters Patent. Patented June 15, 1915.

Original application filed April 16, 1914, Serial No. 839,849. Divided and this application filed January 18, 1915. Serial No. 2,937.

To all whom it may concern:

Be it known that I, GUY L. BONHAM, a citizen of the United States, residing at West Hartford, in the county of Hartford 5 and State of Connecticut, have invented a new and useful Spring-Motor Brake, of which the following is a specification.

The present invention appertains to a spring motor machine adapted to be employed by barbers, masseurs, and others, and 10 is a division of the application filed April 16, 1914, Serial No. 839,849.

It is the object of this invention, to provide a novel thumb or finger operated brake 15 for controlling the speed of rotation of the motor and element actuated thereby, in order that the device may be operated at various speeds, or may be stopped.

It is also within the scope of the invention, to provide a spring motor brake of 20 comparatively simple and inexpensive construction, which will be convenient, efficient and practical in use.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed can be made within the scope of what is claimed without departing from the spirit of the invention.

The invention is illustrated in its preferred embodiment in the accompanying drawings, wherein—

Figure 1 is an elevation of the machine, 40 portions being shown in section. Fig. 2 is an enlarged cross section taken approximately on the line 2—2 of Fig. 1.

In carrying out the invention, there is provided a case or body 1 inclosing the spring motor 2, forming the subject-matter of the application above referred to, the 45 case 1 being carried by a handle 3 engaged to the back of the case 1, while a driven shaft 4 is journaled through the face plate of the case 1, and is adapted to carry a fan or other suitable rotatory element 5 upon 50 its forward or protruding portion.

A plate or member 6 is secured to the inner side of the base plate of the case 1, and is provided with an angular arm or bracket 7 through which the rear or inner 55 end of the shaft 4 is journaled, a spur gear

8 being secured upon the shaft 4 adjacent the arm 7, and intermeshing with a gear of the spring motor 2, in order that the spring motor will rotate the shaft 4.

The brake mechanism for controlling the 60 velocity of rotation of the shaft 4, embodies a brake drum or wheel 9 secured upon the shaft 4 between the spur gear 8 and face or front plate of the case 1, and a brake band or strap 10 partially surrounding the drum 65 10 and having one end attached to the arm 7, as at 11. The brake band or strap 10 extends tangentially, as at 12, from that portion of the drum 9 opposite the end 11 of the brake band, and the other end of the 70 brake band, or the extremity of the tangential portion 12, is attached or pivoted, as at 13, to the end of an inwardly projecting shank 14 of a button 15. The button 15 is 75 slidable or movable upon the periphery of the case 1, and its shank 14 projects through an arcuate slot 16 provided in the periphery of the case. The button 15 is preferably 80 provided with a knob or head 15^a for the engagement of the thumb or finger therewith, in order that the button may be readily slid or moved along the slot 16. A double or bowed leaf spring 17 is attached to the inner end of the shank 14 and its end portions engage or bear against the interior 85 of the case, to hold the button 15 at any position to which it is slid.

Since the shaft 4 is eccentric relative to the case, the portion of the periphery of the case having the slot 16 with which the button is coöperable, will be eccentric relative to the shaft 4, whereby the movement of the button 15 along the periphery of the case will result in the tightening and slackening 90 of the brake band or strap 10. Thus, when the button 15 is at the position nearest the brake drum 9, as seen in Fig. 2, the brake band or strap 10 will be loosened, to enable the shaft 4 to rotate freely and at the greatest velocity, whereas if the button 15 is slid 95 along the slot 16 away from the brake drum 9, the brake band or strap 10 will be brought to frictional contact with the drum 9, for impeding the rotation of the shaft 4. Consequently, by moving the button 15 to various 100 positions, the frictional resistance between the brake drum and the band may be increased or decreased for varying the speed of rotation of the shaft 4, as desired, and when the button 15 is slid sufficiently away 105 110

from the brake drum 9, the brake drum 9 and shaft 4 may be brought to a standstill, to prevent the further unwinding of the spring.

5 As indicated in the above identified application, the present machine may be employed for diverse purposes, the construction and operation of the spring motor and accompanying parts being clearly set forth 10 in the said application. When the handle 3 is held in the hand, the thumb or finger may be readily applied to the button 15 for controlling the rotatory velocity of the fan or other rotatory element 5 carried by the shaft 15 4, and when the machine is not in use, the button 15 may be moved properly for arresting the movement of the spring motor and driven element.

What is claimed is:

20 1. In a device of the character described, a case, a shaft carried thereby, a brake drum carried by the shaft, a brake band having one end anchored to the case and partially surrounding the drum, and a slidible member carried by the case, the other end of the brake band being attached to the slidible member.

30 2. In a device of the character described, a case, a shaft carried thereby, a brake drum carried by the shaft, a brake band having one end anchored to the case and partially surrounding the drum, the case having a slot, and a button slidible along the case and having a shank projecting through the said slot, the other end of the brake band being attached to the said shank.

35 3. In a device of the character described, a case, a shaft carried thereby, a brake drum carried by the shaft, a brake band having one end anchored to the case and partially surrounding the drum, the case having a slot, a button slidible along the case and

having a shank projecting through the said slot, the other end of the brake band being attached to the said shank, and a spring carried by the said shank and bearing against the case.

4. In a device of the character described, a case having a slot in its periphery, a shaft journaled through one portion of the case, that portion of the periphery of the case having the slot being eccentric relative to the case, a brake drum carried by the shaft within the case, a brake band partially surrounding the drum and having one end anchored within the case, and a button slidible upon the periphery of the case and having a portion projecting within the said slot, the other end of the brake band being attached to the button.

5. In a device of the character described, a case having a slot in its periphery, a shaft journaled through one portion of the case, that portion of the periphery of the case having the slot being eccentric relative to the case, a brake drum carried by the shaft within the case, a brake band partially surrounding the drum and having one end anchored within the case, a button slidible upon the periphery of the case and having an inwardly projecting shank working within the said slot, the other end of the brake band being attached to the said shank, and a bowed spring secured to the said shank and having its terminal portions bearing against the interior of the case to hold the button in place.

In testimony that I claim the foregoing as my own, I have hereto affixed my signature in the presence of two witnesses.

GUY L. BONHAM.

Witnesses:

JAMES LIVINGSTON,
H. C. WHITMAN.
